UNITED STATES PATENT OFFICE.

GEORGE E. GOUDIE, OF NORTH EVANSTON, AND HENRY H. HENLEY, OF CHICAGO, ILLINOIS.

DESIGN FOR A PICTURE-FRAME.

SPECIFICATION forming part of Design No. 34,886, dated August 6, 1901.

Application filed July 8, 1901. Serial No. 67,547. Term of patent 14 years.

To all whom it may concern:

Be it known that we, GEORGE E. GOUDIE, residing at North Evanston, and HENRY H. HENLEY, residing at Chicago, in the county 5 of Cook and State of Illinois, citizens of the United States, have invented and produced a new and original Design for a Picture-Frame, of which the following is a specification.

This invention relates to a new and original design for a picture-frame; and the essential features of the design reside in the frame 10 as illustrated in the accompanying facsimile drawings, wherein—

Figure 1 is a plan view of a frame embodying the features of the design. Fig. 2 is a 15 transverse vertical section through a portion of the same to show the body.

The design is characterized by a body 1, having thereon a series of members 2, with 20 arrow-head terminals 3 and transverse enlargements 4 at one extremity of each, the said members being disposed to bring the said enlargements in alternate reverse arrangement. The sides of the frame have cen-

ter panels 5, with twin-pointed ornaments 25 6 in reverse positions at opposite sides. At the center of one end is a number of the members 2, and at the opposite end is a long panel 7, having a plurality of edge ornaments 8, similar to the twin ornaments 6 and also 30 having members 9, approximating the members 2 in shape. The frame also has inwardly and outwardly projecting corner ornaments 10 and adjacent stars 11, trefoils 12, and circularly-indented squares 13. 35

Having thus described the invention, what is claimed as new is—

The design for a picture-frame, herein shown and described.

In testimony that we claim the foregoing as 40 our own we have hereto affixed our signatures in the presence of two witnesses.

GEO. E. GOUDIE.
HENRY H. HENLEY.
